(57) **CLAIM**

The ornamental design for a holding device with sleeve, as shown and described.

DESCRIPTION

FIG. 1 is a front perspective view of a holding device with sleeve showing my new design;
FIG. 2 is a top plan view thereof;
FIG. 3 is a right side view thereof;
FIG. 4 is a left side view thereof;
FIG. 5 is a bottom plan view thereof;
FIG. 6 is a front elevational view thereof; and,
FIG. 7 is a rear elevational view thereof.
The parts shown in broken lines in FIGS. 1-7 form no part of the claimed design.
